UNITED STATES PATENT OFFICE.

SAMUEL E. ADAIR, OF NEW YORK, N. Y., ASSIGNOR TO WESTERN ELECTRIC COMPANY,
INCORPORATED, OF NEW YORK, N. Y., A CORPORATION OF NEW YORK.

ELECTRICAL COIL.

1,409,352.

Specification of Letters Patent. Patented Mar. 14, 1922.

Application filed February 20, 1918. Serial No. 218,279.

To all whom it may concern:

Be it known that I, SAMUEL E. ADAIR, a citizen of United States, residing at New York, in the county of New York, State of New York, have invented certain new and useful Improvements in Electrical Coils, of which the following is a full, clear, concise, and exact description.

This invention relates to electrical coils, and more particularly to such coils used in connection with radio communication for tuning and similar purposes. The object of the invention is to provide a coil in which the distributed capacity is reduced to a minimum.

In continuous layer windings there is a distributed capacity effect within the winding itself due to the difference in potential between turns, this capacity effect being inversely proportional to the spacing between the turns. In many electrical circuits, particularly those in the field of wireless telegraphy and wireless telephony, there is a demand for coils in which the distributed capacity is eliminated or greatly reduced, for example, a coil with such characteristics is particularly desirable as a tuning coil, since it permits much sharper tuning than is otherwise obtainable.

In order to obtain a coil having a low distributed capacity and at the same time one which is not prohibitive in size or difficult to wind commercially, the present invention provides a winding in which the adjacent turns do not lie next to one another but cross one another at a rather blunt angle at frequent intervals around the circumference of the winding.

This construction will be more clearly understood by reference to the accompanying drawing which shows in perspective an inductance coil wound in the proposed manner.

Referring to this drawing, the base member 1, which is preferably of wood or other insulating material, is provided with an odd number of guide pins or spindles which are also of wood or similar material. These spindles, which are numbered 2 to 12, inclusive, are set perpendicularly to the base itself. The insulated conductor 13, one end of which is secured to the terminal 14, is led through a perforation 15 in base 1 and is then given a single turn about the spindle 2 to relieve the winding of any strain.

at the terminal. This conductor is then carried directly to spindle 4, thence to the alternate spindles 6, 8, 10 and 12 in order. From spindle 12, the conductor is carried to spindle 3 and the second turn is made by 60 winding about spindles 3, 5, 7, 9, 11 and 2. Thus, after two complete turns, the conductor is again brought to spindle 2 and the balance of the winding may be placed in the same manner. After completing the 65 last turn, the conductor is given a complete turn around spindle 3 to aid in holding the winding in place and it is then led through the perforation 16 in base 1 and securely fastened to terminal 17. After the winding 70 is completed it is preferably given a coat of shellac at the spindles to prevent shifting of the turns.

With the construction as described and shown on the drawing, it will be noted that 75 adjacent turns come in contact with each other only at the points where they cross between spindles, as at the points 18-18. At all other points they are separated from each other by a distance which reaches a 80 maximum at the spindles. As a result of this increased separation between turns, the distributed capacity of the coil is reduced a considerable amount. Moreover, this reduction in capacity is accomplished without appreciably affecting the size of the coil or without distributing the flux leakage and thereby decreasing the inductance of a coil having a given number of turns.

What is claimed is:

1. An electrical coil comprising a plurality of symmetrical polygon turns adjacent turns having their dihedral angles angularly displaced with respect to each other.

2. An electrical coil comprising a plurality of symmetrical polygon turns, adjacent turns having their dihedral angles angularly displaced with respect to each other, and alternate turns having their dihedral angles in alignment.

3. An electrical coil comprising a base member having a plurality of spindles mounted thereon, said spindles being of an odd number, and a conductor wound upon said spindles, adjacent turns of said winding being angularly displaced with respect to each other and alternate turns being in alignment with each other with respect to their axes.

4. An electrical coil comprising a base

member having an odd number of spindles mounted thereon and perpendicular thereto, mounted thereon and perpendicular thereto, and a winding having a plurality of turns, each of said turns being wound upon 5 alternate spindles.

5. An electrical coil comprising a base member having an odd number of spindles

mounted thereon and perpendicular thereto, and a continuous winding wound successively on alternate spindles.

In witness whereof, I hereunto subscribe my name this 14th day of February A. D., 1918.

SAMUEL E. ADAIR.
